UNITED STATES PATENT OFFICE.

DALLAS A. HOUSTON, OF SPRINGFIELD, ILLINOIS.

STEP-LADDER.

1,109,228.

Specification of Letters Patent.

Patented Sept. 1, 1914.

Application filed April 6, 1912, Serial No. 688,883. Renewed January 21, 1914. Serial No. 813,550.

To all whom it may concern:

Be it known that I, DALLAS A. HOUSTON, citizen of the United States, residing at Springfield, in the county of Sangamon and State of Illinois, have invented certain new and useful Improvements in Step-Ladders, of which the following is a full, clear, and exact description, reference being had to the accompanying drawings, forming a part hereof.

My invention has relation to improvements in step-ladders; and it consists in the novel construction of the ladder more fully set forth in the specification and pointed out in the claim.

In the drawings, Figure 1 is a front elevation of the step-ladder unfolded; Fig. 2 is a side elevation with parts broken away; Fig. 3 is a sectional detail on the line 3—3 of Fig. 2; and Fig. 4 is a cross-section on the line 4—4 of Fig. 2.

The object of my invention is to construct a step-ladder, the ladder section of which shall be composed of a single piece of metal, thereby reducing the number of parts of which the same is formed, the prop member being preferably composed of metal, though not necessarily so.

A further object is to provide a ladder of the character described which shall be simple, durable and cheap to construct.

The advantages of the invention will be more readily apparent from a detailed description thereof which is as follows:—Referring to the drawings, 1 represents an inverted U-shaped frame or member composed of light metal, the sides of the frame having cut therefrom sections or tongues *a*, *a*, of convenient length, so that when the free

ends of two opposite sections (previously bent at right angles to the sides) are brought together and welded at the point *x*, they jointly form a rung or step of the ladder frame, the rungs and frame proper thus forming for all practical purposes a single piece of metal. The cutting or punching of the tongues *a* leaves solid portions *b* between the ends of the rungs or steps thus formed, so that the strength and stiffness of the sides of the ladder are not materially affected. A ladder thus composed of a single unit of metal will last indefinitely and will stand much abuse and long wear. Hinged to the ladder section aforesaid is a prop or frame composed of side members 2, 2, connected by cross-braces 3, 3, a strap 4 connecting the braces at their intersection serving as an anchor for one end of a chain 5 whose opposite end is secured in any mechanical manner to one of the rungs or steps of the ladder frame. The chain of course, limits the degree of angular separation between the ladder and its supporting prop or frame.

Having described my invention, what I claim is:—

A ladder comprising an inverted U-shaped metallic frame, the sides thereof having sections or tongues cut therefrom, said tongues being opposite one another and bent at right angles to the said sides, the free ends of the tongues being welded together to form rungs or steps.

In testimony whereof I affix my signature, in presence of two witnesses.

DALLAS A. HOUSTON.
